UNITED STATES PATENT OFFICE.

EDWARD PERCHAL, OF CHICAGO, ILLINOIS.

DESIGN FOR A CLOCK.

Application filed May 1, 1922. Serial No. 2,032. Term of patent 3½ years.

To all whom it may concern:

Be it known that I, EDWARD PERCHAL, a citizen of the United States, residing at Chicago, in the county of Cook, and State of Illinois, have invented a new, original, and ornamental Design for a Clock, of which the following is a specification, reference being had to the accompanying drawing, forming part thereof.

The figure is a perspective view of a clock showing the new design.

I claim:

The ornamental design for a clock, as shown.

EDWARD PERCHAL.
